UNITED STATES PATENT OFFICE.

PERRY E. HALL, JR., OF EVERETT, WASHINGTON.

GAS-PURIFIER.

No. 824,786.

Specification of Letters Patent.

Patented July 3, 1906.

Application filed December 27, 1905. Serial No. 293,507.

To all whom it may concern:

Be it known that I, PERRY E. HALL, Jr., a citizen of the United States, residing at Everett, in the county of Snohomish and State of Washington, have invented certain new and useful Improvements in Gas - Purifiers, of which the following is a specification, reference being had therein to the accompanying drawings.

10 The invention relates to an improvement in gas-purifiers designed, primarily, for the purification of artificial gas and of the type in which the gas is forced through a suitable purifying agent.

15 As heretofore practiced, the gas has been purified by forcing the same through iron oxid, using for the purpose a plurality of purifying-chambers connected by a system of valves, so that any one of the chambers 20 could be cut out when necessary to clean the purifying agent.

25 It is the object of the present invention to provide a purifier in which but a single purification-chamber is used and in which means are provided for reversing the direction of current of the gas, whereby to clean the filtering agent without the necessity of removing it from the chamber or without the introduction of additional air for this purpose.

30 The invention will be described in the following specification, reference being had particularly to the accompanying drawings, in which—

35 Figure 1 is an end elevation of a purifier constructed in accordance with the invention. Fig. 2 is a similar view with the end plate removed. Fig. 3 is a side elevation of the same. Fig. 4 is a longitudinal section on line 4 4 of Fig. 1, and Fig. 5 is a horizontal 40 sectional view taken on the plane indicated by the line 5 5 in Fig. 4 and showing the inlet and outlet pipes at the ends of the purifier.

45 Referring to the drawings, the improved purifier comprises a metallic box or casing 1 of any desired sectional contour and size, the end walls of 2 which are provided at diametrically opposite corners with ports 3 and 4, respectively. The ports 3 and 4 of the respective end walls are arranged in reverse 50 order—that is, the port 3 at one end of the casing is directly opposite the port 4 at the opposite end of the casing, though said ports are respectively arranged at the upper and lower portions of the casing. By this arrangement the ports 3 are arranged in aline-

ment transverse the length of the casing, but at opposite side edges of the respective end walls, as clearly shown in full and dotted lines in Fig. 2. Within the casing 1 is arranged a grate 5, positioned above the respective openings 4, on which grate the filtering agent is to be supported, it being understood that the upper surface of said material is below the openings 3. The side walls of the casing are provided with suitable doors 6, which may be of any preferred type, for sealing the openings, through which doors the filtering material may be removed or replaced, as desired.

55 A chamber 7 is provided at each end of the casing 1, the chamber at one end being for the inlet of the gases and the chamber at the opposite end for the outlet of the gases, and each chamber is preferably formed by securing a wall 8 to and spaced from one of the end walls of the casing. This chamber is divided by vertically-arranged partitions 9 and 10, each of the partitions extending transverse the chamber from the casing end wall to the wall 8. The partitions 9 extend 60 from the upper wall 8 of the chamber 7 and terminate above the lower wall thereof, while the partitions 10 are arranged alternately with the partitions 9 and extend from the lower wall of the chamber 7 toward the upper 65 wall, terminating a short distance from said upper wall. By this construction the partitions, preferably four in number, divide the chamber 7, hereinafter termed the "feed-chamber," into five compartments 11, 12, 13, 14, and 15, successively in communication at 70 opposite ends, providing a tortuous passage transverse the chamber 7. It will be noted that the respective openings 3 and 4 are of practically the full width of the respective 75 compartments in which they are located and that the partition adjacent said port closes the compartment in direct communication with the port against the successive compartment except at the end of the chamber remote from said port. The gas is admitted 80 to the chamber 7 through a pipe 16, in communication with a source of supply and opening into the chamber near the upper edge of the top wall thereof, being preferably so located as to directly communicate 85 with the central compartment 13 of the feed-chamber. It is understood that as the chamber 7 at the opposite end of the casing 90 is identical with that described the pipe 16 in 95 100 105 110

communication therewith will serve as a discharge or service pipe from the purifier. As described, it is obvious that the admission of gas through the pipe 16 will cause said gas to pass into the purifier through the ports 3 or 4 at the feed end of the purifier and out the ports 3 or 4 at the opposite end of the purifier. As these respective ports, however, are positioned above and below the purifying medium, it is obvious that if such operation were permitted the gas would not be compelled to traverse the purifying medium at all. It has been heretofore proposed to provide a series of complicated valve structures by which the gas may be compelled to travel through the filtering medium in the direction desired; but owing to the complication in structure and operation of such valve mechanism the results have not been wholly satisfactory. The present invention aims to obviate this difficulty by providing a simple controlling means by which the gas may be directed into the casing through either of the ports 3 or 4, a similar and simultaneously-operating means being located in the exit-chamber of the purifier to close the port reversely located relative to the port opened in the feed-chamber, so that the gas is compelled in its traverse of the purifying-casing to pass entirely through the purifying agent. The means to this end comprises a sealing medium, such as water or other liquid, (shown at 17,) in the chamber 7 and in such quantity as, when in the compartments 13 and 14 or 11 and 12, as the case may be, to seal and close the opening below the respective partitions 9. To control and regulate the position of the sealing medium, the compartments 14 and 12 are in communication through spaced pipes 18 and 19, and the respective pipes 19 of each chamber 7 are in communication through pipes 20, extending longitudinally of and beneath the casing 1. A suitably-operated transferring device, as a pump 21, is in communication with the pipes 18 and 19 and is adapted in operation to transfer the sealing medium in the respective chambers from the compartments 13 and 14 to the compartments 11 and 12, or vice versa. Sight-gages 22 of usual type are in communication with the compartments 14 and 12, respectively, enabling the operator to have a visual knowledge of the condition of the sealing medium and for another purpose to be later described. In use, assuming that the sealing medium is positioned in the compartments 13 and 14, thereby closing the passage below the partition 9, dividing these compartments and effectively sealing them against each other, this condition being duplicated at the opposite or delivery end of the purifier, the gas admitted through the pipe 16 is thereby compelled to travel into the compartment 12 beneath the partition 9 and up through the compartment 11 and through the port 3.

The compartments 11 and 12 of the delivery end of the casing are in communication in the new position of the seal; but as these compartments communicate with the port 4, which is located below the purifying medium, the gas is compelled to pass wholly through the body of the purifying material in order to reach the outlet-port. When desiring to reverse the direction of current of the gas, the pump is operated to transfer the sealing medium to prevent passage of the gas below the partition 9, separating the compartments 11 and 12. In this condition the gas is compelled to pass through the port 4 on its entrance to the casing 1 and up through the purifying material to the upper port 3 at the outlet end of the casing. A deflecting plate or box 23 is placed inside of the purifying-chamber at each of its ends and adjacent to its bottom to conduct the gas to the reverse side of said chamber, so that it will be necessary for the gas to pass the greatest possible distance diametrically through the oxid on its course to the outlet-port.

As clearly shown in Fig. 5 of the drawings, the deflector plates or boxes 23 extend transversely of the purifier beneath its false bottom or grate 5, on which the purifying medium is supported, and each of said boxes has its outer end opening into the lower end of one of the compartments 5 and its other open end terminating a short distance from the opposite side of the purifier, so that the gas must take the longest course from one corner of the purifying-chamber to the corner diagonally opposite, as indicated by the arrows in Figs. 4 and 5. By the reversal of the current described I am enabled to clean up the deteriorated purifying agent without removing the material from the box or without introducing air in combination with the gas. No intricate valve mechanism is required for the reverse operation, and the direction of flow of the gas is readily and instantly controlled.

By the use of the sight-gages the operator is enabled to readily determine the condition and position of the sealing medium and to also readily detect the presence of any back pressure incident to an imperfect operation of the device. The box or casing 1 may also be provided with manholes, preferably on top thereof, for use in properly ventilating the same when making repairs or the like or for the purposes of inspection.

The particular details of construction of the purifier, aside from the features hereinbefore described, are immaterial so far as this invention is described, and I wish it understood that I do not limit myself to any particular size of purifier, shape, or material therefor.

It will also be readily understood that two or more boxes may be installed, as may be found desirable. Preferably two boxes are installed, one being designed as a reserve-

box, for the reason that eventually the oxid will become exhausted and unfitted for use and will have to be renewed.

Having thus described my said invention, 5 what I claim as new, and desire to secure by Letters Patent of the United States, is—

1. A gas-purifier comprising a casing arranged to contain a purifying agent, one wall of the casing being formed with ports, a chamber at said wall of the casing and in open communication with said ports, said chamber being divided into communicating compartments, a liquid seal in one of said compartments, and means for transferring said seal 15 from one compartment to another.

2. A gas-purifier comprising a casing arranged to contain a purifying agent, one wall of the casing being formed with ports, a chamber at said wall of the casing and in open communication with said ports, said chamber being divided into communicating compartments, a liquid seal in one of said compartments, and a pump having connections with 20 said compartments for transferring said seal from one compartment to another.

3. A gas-purifier comprising a casing arranged to contain a purifying agent, the walls of said casing being formed with ports, chambers at the walls of said casing and in open 30 communication with the ports, said chambers being divided into communicating compartments, a liquid seal in one of said compartments, and means for transferring said seal from one compartment to another.

4. A gas-purifier comprising a casing arranged to contain a purifying agent, the walls of said casing being formed with ports, chambers at the walls of said casing and in open communication with the ports, said chambers being divided into communicating compartments, a liquid seal in one compartment of each of said chambers, and means for transferring said seals from one to another of said compartments to close any of said ports for 40 the purpose set forth.

5. A gas-purifier comprising a casing arranged to contain a purifying agent, the end walls of the casing being formed with ports, the ports being positioned at top and bottom 50 of each wall respectively, chambers provided opposite each other in the casing and in open communication with the ports, said chambers being divided into communicating compartments, a liquid seal in one compartment of each of said chambers, and means for transferring said seals from certain of said compartments to certain other of said compartments.

6. A gas-purifier comprising a casing arranged to contain a purifying agent, the end 60 walls of the casing being formed with ports, the ports being positioned at top and bottom of each wall respectively, chambers provided opposite each other in the casing and in open communication with the ports, said chambers being divided into communicating compartments, a liquid seal in one compartment of each of said chambers, and means for transferring said seals from one to another of said compartments to close oppositely - located 65 ports in the respective end walls of said casing.

7. A gas-purifier comprising a casing arranged to contain a purifying agent, the end 70 walls of the casing being formed with ports, the ports of each wall being in diagonal alignment relative to each other and to the ports of the other wall, chambers at the ends of said casing divided into communicating compartments and in open communication with the 80 ports, a liquid seal in one compartment of each of said chambers, and means for transferring said seals from one of said compartments to another of said compartments.

8. A gas-purifier comprising a casing having end walls each formed with diagonally-aligned ports, a grating within the casing and adapted to support a purifying agent a chamber at each end of the casing and divided into a plurality of communicating compartments, 90 said compartments being in communication with the casing-ports, a liquid seal for one of said compartments to prevent passage of the gas through one of the ports, and means to transfer said seal from one compartment to 95 another to reverse the flow of the gas.

9. A gas-purifier comprising a casing arranged to contain a purifying agent, the walls of said casing being formed with ports, chambers provided at opposite ends of said casing 100 and in open communication with said ports, said chambers being divided into communicating compartments, a liquid seal in one compartment of each of said chambers, pipes connecting the compartments of the chambers at opposite ends of the casing, and means for forcing said liquid seals through said pipes from one compartment to another, substantially as described and for the purpose set forth.

In testimony whereof I hereunto affix my signature in presence of two witnesses.
